COMB ATTACHMENT FOR CARPET SWEEPERS

Earle R. Smith, Alhambra, Calif., assignor, by
mesne assignments, to Earl F. Callan

Application May 24, 1933, Serial No. 672,606

7 Claims. (Cl. 15—48)

My invention relates to comb attachments for carpet sweepers, and it has particular reference to comb attachments of the type embodied in my Patent No. 1,898,318 issued February 21, 1933.

As disclosed in my patent, two combs are disposed at opposite sides of the sweeper brush, and they are so mounted in the sweeper box that they tend to gravitate to stripping positions with relation to the brush, but are movable to non-stripping positions alternately, by and according as the brush rotates in one direction or the other.

In order that the combs may properly gravitate to stripping positions extreme precision is necessary both in constructing and mounting the combs. Further, prolonged use of the sweeper causes such wear of the brush journals that lateral play of the brush develops. This results in failure of the proper operation of the combs in the brush so that the combs are no longer fully effective to remove accumulations from the brush.

It is a purpose of my invention to provide a comb attachment for carpet sweepers in which two combs are operatively connected one to the other to occupy stripping and non-stripping positions, respectively, and to be reversed positively in their respective positions according as the sweeper brush is reversed in its direction of rotation. By my mechanism is eliminated need of extreme precision in mounting the combs, and the dependence upon gravity to move the combs is completely avoided.

It is also a purpose of my invention to provide a comb attachment a part of which has physical contact with the surface being swept to positively move one or two combs from stripping to non-stripping position or vice versa according as the sweeper box is moved in one direction or the other, and in the two comb arrangement to effect reversal in the relative positions of the two combs concurrently with reversal in directional movement of the sweeper.

I will describe only two forms of comb attachments for carpet sweepers embodying my invention and will then point out the novel features thereof in claims.

In the accompanying drawing;

Fig. 1 is a fragmentary top plan view of a carpet sweeper with the top thereof removed, and having incorporated therein one form of comb attachment embodying my invention.

Fig. 2 is a transverse sectional view taken on the line 2—2 and looking in the direction of the arrows.

Fig. 3 is a view similar to Fig. 1 showing another form of comb attachment embodying my invention.

Fig. 4 is a transverse sectional view taken on the line 4—4 of Fig. 3 and looking in the direction of the arrows.

In both embodiments of my invention they are shown applied to a conventional form of carpet sweeper shown as including a box B mounted for rolling movement on wheels W. A brush D is rotatable in journals J, and by means of the wheels W, the brush can be rotated in either direction according as the sweeper is moved forwardly or rearwardly over the surface being swept. Dust pans P are secured in the sweeper box at opposite sides of the brush to collect dust and other matter removed from the floor by the brush.

The comb attachment shown in Figs. 1 and 2, comprises a pair of combs C and C' situated at opposite sides of the brush D, and although they are reversely arranged, their specific construction and manner of mounting is identical, so that a description of one will suffice for both.

Each comb C or C' comprises an elongated body 15 approximately corresponding in length to the distance between the confronting faces of the end walls of the box B so as to be coextensive in length with the brush D. Teeth 16 are formed integral with the body 15 and so as to extend upwardly therefrom. The opposite ends of the body are bent at right angles to form ears 17 pivotally mounted on the end walls of the box by pins 18, and in this manner the comb as a whole is mounted for pivotal movement in the box.

As best shown in Fig. 2, the two combs C and C' are operatively connected one to the other by means of a connector 19. This connector is provided for the purpose of transmitting the motion of one comb to that of the other in order that when either comb is moved from one position by the brush, the other comb as a result, is moved likewise, but to occupy a different position with relation to the brush.

In the present instance this connector is in the form of an arched rod with its ends bent to form pintles 20 which extend into the ears 17 at points above the pivot pins 18. The usual stop pins such as disclosed in my patent hereinbefore referred to, may be employed to limit inward swinging movement of the combs to define their stripping positions in relation to the brush.

During the reciprocating movements of the sweeper over a surface being swept thereby, the

operation of the comb attachment just described, is as follows:

With the brush rotating in a counter-clockwise direction as indicated by the arrow in Fig. 2, the 5 comb C occupies the inner extreme position shown. I term this position a stripping position for the reason that the teeth of the comb project into the brush to strip or remove from the brush dust, lint and other matter accumulated on the 10 brush, and to cause such matter to be deposited into the adjacent pan. The other comb C', meanwhile, occupies an outer extreme position which I term a non-stripping position because, 15 its teeth are removed from between the brush bristles so that they have no stripping action relative to the brush.

The comb C' is initially moved to non-stripping position by the brush itself for it will be clear that with the brush bristles moving upward at 20 this side of the brush and the comb in stripping position, such bristle movement will swing the comb upward to the non-stripping position shown. Concurrently with elevation of the comb C' to non-stripping position the connector 19 moves to the left to lower the comb C to the 25 stripping position shown.

As long as the brush rotates in this counter-clockwise direction the two combs occupy the 30 positions illustrated so that the comb continues to remove accumulations from the brush and cause them to be deposited into the respective pan.

However, when rotation of the brush is reversed by reversing movement of the sweeper, 35 the comb C' is moved by the brush into stripping position, while the comb C is simultaneously elevated to non-stripping position under movement of the connector in the opposite direction. Thus the comb C' now functions to strip the brush of 40 accumulations for subsequent deposit into the respective pan.

From the preceding operation, it will be manifest that the mounting of and the connection between the two combs does, under rotative 45 movement of the brush, effect positive movement of one comb or the other to non-stripping position according as the brush is rotated in one direction or the other, and with such movement the other comb is simultaneously moved to stripping 50 position.

Referring now to Figs. 3 and 4, I have here shown another form of comb attachment which embodies the same two combs C and C' in the same relation to the brush D, and mounted in the 55 same manner to occupy stripping and non-stripping position. However, in this embodiment, the brush is not relied upon necessarily to move the combs to non-stripping position as in the first form of my invention for I provide a means 60 wholly independent of the brush for actuating the combs.

This means comprises an arm 21 and a brush 22 on the lower end of the arm, the two constituting an actuator for a rod 23 which operatively 65 connects one comb to the other in the same manner as the rod 19. The arm 21 is pivoted by a pin 24 on the inner side of one end wall of the box B for rocking movement, and it is operatively connected to the rod 23 by a lug 25 which 70 works in an upwardly bent part 26 of the rod. Thus as the arm is rocked in one direction or the other, the rod is moved lengthwise in one direction or the other to cause the combs to occupy stripping and non-stripping positions alternately. As in the first form of my invention, 75

conventional stop pins such as disclosed in my patent hereinbefore referred to, may be employed to define the stripping positions of the two combs.

Rocking of arm 21 to either extreme position is effected through the medium of the brush 22. The bristles of this brush are of such length as to not only have contact with the rug or other surface being swept but to be flexed when in engagement therewith and thus sufficient traction or friction is set up between the bristles and the rug to effect movement of the arm 21 with each change in direction of movement of the brush 22.

The operation of my comb attachment, under the normal reciprocating movements of the sweeper box, is as follows:

With movement of the sweeper box to the right (Fig. 4), the arm 21 occupies the position shown in Fig. 4 and in this position the comb C' is in non-stripping position while the comb C is in stripping position to remove accumulations from 20 the brush D as the latter is rotated in a counter-clockwise direction. During this movement of the sweeper box the brush 22 being dragged along the floor remains flexed and sufficiently rigid to maintain the arm in the extreme position shown. 25

When the sweeper box is moved to the left, the brush 22 is immediately flexed in the opposite direction to that shown in Fig. 4, and under continued movement of the box the arm 21 is rocked to a reverse position thereby actuating the rod 30 to reverse the position of the combs. Thus the comb C now occupies non-stripping position and the comb C' stripping position to remove accumulations from the brush D as it rotates in a clockwise direction.

From this mode of operation, it will be seen that the brush 22 in its dragging contact with the surface being swept, is operable automatically to positively actuate and reverse the positions of the two combs with each reversal in 40 direction of movement of the sweeper box, so that the combs at all times operate in the intended manner to remove accumulations from the brush and guide them into the pans.

Should it be desired to employ my attachment 45 where only a single comb is used, that portion of the rod extending to either side of the bent part 26 depending upon which comb is eliminated, is dispensed with. As will be understood the remainder of the rod will continue to provide 50 an operative connection between the remaining comb and the arm so that under rocking movement of the latter engendered by the flexing movements of the brush, the comb is positively moved to stripping or non-stripping position as 55 determined by the direction of movement of the sweeper box.

Although I have herein shown and described only two forms of comb attachments for carpet sweepers, each embodying my invention, it is to 60 be understood that various changes and modifications may be made herein without departing from the spirit of my invention and the spirit and scope of the appended claims.

I claim:

1. A carpet sweeper having a brush rotatable in either direction; a pair of combs; means for mounting said combs at opposite sides of said brush so that each comb is movable to occupy either a stripping or a non-stripping position 70 with relation to the brush, and when in stripping position to be moved to non-stripping position by the bristles of said brush when the latter is rotated in one of its two directions; and a connection between the combs for transmitting the mo- 75

tion of that comb being moved to non-stripping position by the brush, to the other comb so as to simultaneously move the latter to stripping position.

5. 2. In a carpet sweeper; a box; a rotary brush in the box; a comb at one side of the brush and pivoted in the box to occupy either a stripping or a non-stripping position with relation to the brush; and an actuator connected to the comb and positioned to have contact with the surface being swept so as to move the comb from one of said positions to the other according as the box is moved in one direction or the other, said actuator comprising an arm connected to the comb and having a resilient terminal portion adapted for wiping engagement with said surface.
10. 3. In a carpet sweeper; a box; a rotary brush in the box; a comb at one side of the brush and pivoted in the box to occupy either a stripping or a non-stripping position with relation to the brush; and an actuator connected to the comb and positioned to have contact with the surface being swept so as to move the comb from one of said positions to the other according as the box is moved in one direction or the other, said actuator comprising an arm connected to the comb and having a brush at its lower end.
15. 4. A carpet sweeper having a brush rotatable in either direction; a pair of combs; means for mounting said combs at opposite sides of said brush so that each comb is movable to occupy either a stripping or a non-stripping position with relation to the brush, and when in stripping position to be moved to non-stripping position by the bristles of said brush when the latter is rotated in one of its two directions; and a rod so connecting the combs that according as one comb is moved to non-stripping position by the brush

the other comb will be moved by the rod to stripping position.

5. A carpet sweeper having a rotary brush; a comb mounted parallel and adjacent to the brush and movable to either stripping or non-stripping position; a movable member positioned to drag on the surface being swept by the brush; and a connection between said member and said comb arranged to move the comb into one or the other of said positions as the member is dragged in one direction or the other by the movement of said surface with respect to the sweeper.

6. A carpet sweeper having a rotary brush; a pair of combs mounted parallel and adjacent to the brush at opposite sides thereof and each movable to either a stripping position or a non-stripping position; a movable member positioned to drag on the surface being swept by the brush; and a connection between said member and said combs arranged to move one comb into one or the other of said positions and the other comb into a position opposite to the position of the first comb according as the member is dragged in one direction or the other by movement of the sweeper over said surface.

7. A carpet sweeper having a box; a pair of combs; means for mounting the combs in the box to occupy either a stripping position or a non-stripping position; a connection between said combs for causing one of said combs to be moved to a stripping position concurrently with movement of the other of said combs to a non-stripping position; and a brush so rotatable between said combs that according as the brush is rotated in one direction or the other it will move one comb or the other to non-stripping position.

EARLE R. SMITH.
